Walter E. Rose

D. J. Dallamini
ATTORNEY.

UNITED STATES PATENT OFFICE

WALTER E. ROSE, OF DENVER, COLORADO, ASSIGNOR OF ONE-HALF TO C. W. ROSE,
OF DENVER, COLORADO

SUPPORT FOR WINDOW CLEANERS

Application filed March 1, 1927. Serial No. 171,779.

This invention relates to supports for window cleaners and its main object resides in the provision of a gear of simple construction which can be suspended from a window sill in such a manner as to provide a safe and secure support upon which a person can stand outside the window in a position to clean the upper and lower sashes thereof.

10 A further object of the invention is to provide in association with a support of the above described character, a belt for the support of the body of the cleaner, another object is to render both the support 15 and the belt adjustable by simple means so that the device can be fitted to windows of different sizes and forms and made applicable to persons of different heights.

Another object resides in providing a support for window cleaners which is held without the use of hooks, eyes or similar fastening devices on the window frames or other parts of the building and which permits of the window being closed while the 25 operator is outside the same, and still other objects reside in details of construction as will fully appear in the course of the following description.

In the accompanying drawings in which 30 like characters of reference designate corresponding parts throughout the views,

Figure 1 represents a sectional elevation of a window showing the support in its operative position with relation thereto,

35 Figure 2, a fragmentary horizontal section through the window, taken on the line 2-2 Figure 1, and drawn to an enlarged scale,

Figure 3, a perspective view of the support gear,

40 Figure 4, an enlarged section of the support, along the line 4-4 Figure 2, the window sill having been omitted,

Figure 5, a section similar to that shown 45 in Figure 2, showing a modification in the construction of the fastening means of the support,

Figure 6, a section taken on the line 6-6 Figure 5,

50 Figure 7, a section similar to that of Fig-

ure 6, showing another modification in the construction of the support, and

Figures 8 and 9, fragmentary elevations showing variations in the construction of, the foot support included in the invention. 55

Referring further to the drawings the support as illustrated in Figures 1 and 3, comprises two straps 5 of suitable material, doubled at their lower ends to provide stirrups 6 adapted to admit the feet of the 60 operator. The stirrups which conjointly provide a support for the feet of the person standing outside the window, are formed by riveting the ends of the doubled straps as at 7 and they are reenforced by metal foot 65 plates 8.

Transverse straps 9 fastened on the straps above the stirrups are provided with buckles 10 to embrace the ankles of a person standing in the stirrups and thereby hold the feet 70 in place. Adjustably secured adjacent the opposite ends of the straps, are flat anchor-hooks 12 which in the operation clasp the window sill 13 at the inside of the wall 14 as best shown in Figure 1. 75

The straps are adjustably fastened to the hooks by weaving the end portions thereof through parallel slots in the flat shanks 12^a of the hook, between flanges 12^b which reinforce the hooks at opposite sides thereof. 80

The hooks are preferably lined with leather or other soft material as at 15, to prevent marring of the sills to which they are applied. When the hooks are placed in their operative position relative to a window sill the straps extend across the sill and the wall of the building in which the window is fastened, so that the stirrups hang outside the wall to support the window cleaner in an upright position as shown in Figure 1. 85

At the points at which the straps bend across the edge of the wall, they are provided with saddles 16 of rubber or other flexible material, which protect the straps against wear. The saddles are held in place on the straps by loops 17 which permit of the adjustment of the saddles along the straps and relative to the hooks, in accord- 90
95
100

ance with the width of the wall to which the support is applied.

Secured to the straps at points between the anchor hooks and the saddles, is a belt consisting of a strap 18 having its ends 5 adjustably fastened to the straps of the support, and two shorter straps 19 and 20 which are attached to the other and which may be fastened together by means of a buckle 21.

10 The belt thus associated with the support is fastened around the body of a window cleaner standing in the stirrups to prevent him from falling backward.

15 The adjustable connection between the ends of the belt straps 18 and the straps 5 of the support are established by means of metal buckles 22 composed of flanged plates provided with parallel slots through which the straps are woven as best shown 20 in Figure 4 of the drawings.

In order to hold the saddles in place on the straps, they may be fastened to the buckles 22 by means of short straps 23 connected by buckles 24.

25 It will be observed that when the support is applied to the window sill as shown in the drawings and hereinbefore described, the only parts passing underneath the window sashes are the flat straps 5 so that the sashes 30 may be lowered to the sill when the cleaner is outside the window and are thus easily reached.

The gear anchored on the sill will support the operator with the utmost safety and the 35 adjustability of the parts of which it is composed permits of its use on sills and walls of different thicknesses and at the most convenient distances beneath the opening of the window.

40 Having thus described the support in its preferred form, it is to be understood that variations and changes in the construction and arrangement of the constituent members thereof may be resorted to without departing 45 from the spirit of the invention. For example, in places where a window sill of sufficient size or strength is not available, the straps 5 may be secured by means of a strong rod 25 placed across the window 50 frame on the inside of the building as illustrated in Figures 5, 6 and 7. The hooks on the straps may then clasp the rod as shown in Figures 5 and 6 or the straps may be fastened to the rod by loops 26 as illustrated 55 in Figure 7.

The foot support which in the preferred form of the invention, is represented by the stirrups 6, is also subject to variations. In the construction shown in Figure 7, a platform 60 form 27 is suspended from the ends of the straps by means of bails 28, and this platform may be provided with straps 29 to secure the legs of the cleaner, if so desired.

The platform may also be provided with 65 sides to form a basket or box 30 in which

the operator can stand, or a short ladder 31 may be suspended from the straps 5 so that the cleaner can change his position above the window sill to reach different parts of the window sashes.

70 The last-mentioned modifications have been shown in simple form in Figures 8 and 9.

75 The means for fastening the straps and for adjusting the length and relative positions thereof may also be changed within the scope of the invention.

80 It is to be understood that while straps of the kind shown in the drawings are preferable, any other flexible means such as thin metal strips, chains or ropes may be employed within the scope of the invention.

Having thus described my invention, what I claim and desire to secure by Letters Patent is:—

85 1. An appliance of the character described comprising a support for the feet, straps to suspend the support outside a window, means to anchor the straps inside the window, and flexible saddles connected on the straps, to engage the edge of the wall outside the window.

90 2. An appliance of the character described comprising a support for the feet, straps to suspend the support outside a window, 95 means for anchoring the straps inside the window, a strap adapted to embrace the body of a person standing on the support, and buckles having pluralities of slots, the suspension straps and the ends of the body 100 strap being woven through the slots of each buckle.

105 3. An appliance of the character described comprising a support for the feet, straps connected with the support to suspend the same outside a window, and anchor hooks to clasp the sill inside the window, having pluralities of slots through which the straps are woven.

110 4. An appliance of the character described comprising a foot support, a strap for suspending the support outside a window, means for anchoring the strap inside the window, and a body belt including a strap fastened to the suspension strap and adapted 115 to embrace the body of a person standing on the support.

120 5. An appliance of the character described comprising an element having opposed members forming a loop, anchoring means at the free ends of the members, stirrups suspended from the members, and a body embracing means in the loop between the members.

125 6. An appliance of the character described comprising two suspension members, a body strap having opposite portions connected with the suspension members, and stirrups separately connected with the suspension members.

130 7. An appliance of the character described

comprising two anchoring means, a foot support connected with each anchoring means, and a body belt connected with each anchoring means and with each foot support.

⁵ In testimony whereof I have affixed my signature.

WALTER E. ROSE.
